(57) **CLAIM**

The ornamental design for a cleaning mitt, as shown and described.

DESCRIPTION

FIG. 1 is perspective view a cleaning mitt, showing my new design.

FIG. 2 is a top plan view thereof.

FIG. 3 is a bottom plan view thereof.

FIG. 4 is a left-side elevational view thereof, the right-side elevational view is a mirror image thereof.

FIG. 5 is a front elevational view thereof.

FIG. 6 is rear elevational view thereof; and,

FIG. 7 is an exploded perspective view thereof, showing the removable pad separated from the body of the mitt.

The textured patterns are fragmentarily shown for convenience of illustration. It is understood that the patterns are uniformly continuous over the respective panels.
